BUFFING DRUM

Joseph Leigh Smith, Glen Ellyn, Ill.

Application January 25, 1946, Serial No. 643,300

10 Claims. (Cl. 51—194)

1

The subject of this invention is a buffing drum for holding emery cloth.

In order to understand the relationship of applicant's drum to the problems which it overcomes, a statement of existing commercial art will be helpful. The type of drum most commonly used today on applications where the drum has a diameter of four inches or less consists of a shaft having mounted thereon a cylindrical rubber core (solid or air-filled) of compressible characteristics disposed between two metal discs together with means for pressing the two metal discs toward each other against the opposite ends of the cylindrical rubber core so as to compress the core and expand it radially. Before tightening the discs against the core, a preformed sleeve of emery cloth is positioned around the rubber core and the clearance is so little that when the core is expanded by tightening up the discs, the emery sleeve is held tightly in position. The cost of a sleeve is several times the cost of the strip emery cloth from which it is made. In use, this assembly performs well when the R. P. M. does not exceed 5,000. When these drums are placed on tools which turn 7,000 to 20,000 R. P. M.—tools which are very common today—the rubber core lacks sufficiently uniform tensile strength to prevent the development of bulges in the rubber core due to centrifugal force. While these bulges are undesirable because they may impair the uniformity of the finishing, the most serious objection to a bulge arises from the fact that it unbalances the drum so that the assembly pounds violently. It is not practical to utilize this rubber core type of construction where the R. P. M. exceeds what has become a comparatively low figure. This undesirable development of bulges has been reduced by providing the emery sleeves with a comparatively strong backer or innerliner. These sleeves are referred to as stiff back sleeves.

In the case of drums having a diameter of four inches or more, that most commonly in use consists of a split drum or a solid drum having a split in its surface parallel to its axis, for which is provided a strip of emery cloth which has its ends clipped together like the points of joinder of the inwardly directed portion of the conventional heart-shape figure. The clipped together ends are inserted in the slot and on the inside of the drum is a spindle to which the ends are fastened. By means of a key the spindle is pulled up tight and the emery cloth is drawn tightly around the drum. This form of drum can be operated at high speeds, but the construction for pulling up

5 the ends of the emery cloth requires so much space that commercially, drums having a radius of less than four inches are not available. This type of locking spindle does not lend itself to a reduction in size so as to fit within a one-half, one- or two-inch drum while still providing sufficient grip to hold and facility to interchange the ends of the emery cloth.

10 It is frequently desirable in the case of a metal drum to interpose a thin compressible surface such as felt between the drum and the emery cloth.

15 In the case of these two types of emery cloth sleeves, it is difficult to pack them. The reason is that the life of the sleeve would be impaired if it were folded, the fold creating a cracked condition in the emery surface which with use quickly increases. The result is that in the case of the closed type of sleeve, it is difficult to place more than half a dozen inside of one in order to ship. Stiff back sleeves cannot be nested at all. Five hundred stiff-backed sleeves one-inch in diameter and four inches wide occupy a cubic foot. In a recent shipment of these stiff backed sleeves to 20 Russia, an entire railroad freight box car was loaded with boxes containing the sleeves and the sleeves themselves did not weigh much over one ton. Shipping the same amount of emery cloth cut to proper width and length would have required one-tenth to one-twentieth of the space.

25 The foregoing indicates that the commercial emery cloth buffering field is dominated by the emery cloth sleeve, one type being a true sleeve while the other type has the two ends clipped together for insertion in a drum slot. The sleeve dominates the field even though the strip emery cloth of equal area costs but a fifth or sixth of a sleeve of equal area and even though the cost of shipping the emery strips is but a fraction of the cost of shipping the sleeves. It should be understood that the manufacturers of the sleeves buy the emery cloth in strip form.

30 35 40 45 50 55 The commercial advantages possessed by the sleeves over the strip emery cloth are two in number: firstly, users can interchangeably mount on a single drum emery cloth sleeves having a full grit range, whereas a user of drums for holding emery cloth strips must have several drums of a given diameter each intended to accommodate emery cloth strips having a limited grit range; and secondly, sleeves lend themselves to rapid interchangeability while being tightly held on the drum when in locked position, whereas existing drums or drum designs firmly grasp the emery cloth only after considerable adjustment which

workmen frequently will not perform with care. These will be discussed in order.

Emery cloth is manufactured in a wide range of grits. Applicant is particularly interested in emery cloth having a grit range from 50 to 250 because in the finishing of most steel, emery cloths having this grit range are used. The figures identify the size of openings in the screens for the particles which are actually deposited on the cloth to form the emery cloth. The lower the number, the larger the particle, and this is what is important, the thicker the emery cloth. A 50 grit emery cloth is twice as thick as a 250 grit emery cloth. Each grinding job can best and most rapidly be performed by a given emery cloth of a particular coarseness or fineness. It is self-evident that in the case of sleeves, the thickness of the emery cloth is immaterial. The manufacturer of sleeves simply maintains his inside diameter, and this enables the workmen to use a single drum for a sleeve of any emery cloth grit. In the case of drums for strip emery cloth, however, the thickness of the emery cloth has thus far made it impossible to provide a locking means in a single drum which will accommodate a wide range of emery cloth thicknesses while locking the ends equally tightly, and what is very important, quickly. A workman can untighten a screw on a rubber drum, slip off a worn sleeve and put on a new sleeve quickly. Any drum that requires fumbling with the free ends of a strip of emery cloth and the tightening of complicated end holding means with substantial likelihood of unequally tightening, cannot compete. Existing drums for strip emery cloth have locking means designed to accommodate a given thickness of cloth. One designed to grip a 100-grit emery cloth may not even engage a 250-grit cloth. The result is that one must have several drums of the same size or one drum with a plurality of interchangeable locking means in order to accommodate a full range of emery cloth grits. This fact has commercially killed several small drums having satisfactorily fast locking means for a given thickness of cloth only. An industry will maintain a plurality of drums of different diameters, but rather than buy a plurality of the same size drums with different locking means, it will buy the more expensive sleeves.

The second reason has been partly touched upon, namely the rapid interchangeability of sleeves as compared with strip emery cloth. A drum for holding strip emery cloth is unsatisfactory if it does not hold the emery cloth evenly and tightly around the drum surface, or if it requires time consuming manual adjustments in order to effect such a tight even holding of the emery cloth. What is wanted is a locking means which moves from open to locked position by a single turning movement and which maintains itself in locked position without the aid of pawls, etc. Such a locking means is difficult to devise because the emery surface is outwardly directed on the drum and the emery surfaces face each other when brought inwardly of the drum and some proposed locking means therefor have engaged a smooth surface in order to grip the ends of the strip—and such locking means do not hold well.

The first object of this invention is to provide a small drum for emery cloth strips which may be operated at speeds up to twenty thousand revolutions per minute.

A second object of this invention is to provide a locking means which upon a single turn of

the wrist first locks one end of the cloth and then grips the emery surface of the other end of the strip and by pulling it inwardly tightens it around the drum. A feature of this invention is a lock shoe which on a first partial turn of the locking means grips one end of the emery cloth strip, and a tension shoe which on further movement of the locking means in the same direction first grips the other end of the strip and then tightens the strip around the drum. Turning the wrist in one direction first locks one end of the strip, then the other, and then tightens the strip around the drum.

The third object of this invention is to provide a small drum which without change of parts will accommodate strip emery cloth having a wide range of thickness. Ancillary to this object is a desire to locate the locking means axially of the drum so as to aid exact balancing of the drum.

Two embodiments of the principal invention are illustrated. The first has locking and tension shoes of uniform thickness and the second has locking and tension shoes of tapered thickness which act as a cam. There is also shown an adaptation of applicant's preferred locking means to a drum having a diameter of four inches or more. It is necessary to provide an arbor axially of larger drums and consequently it is necessary to locate applicant's locking means. A third embodiment of the invention shows such relocation of the locking means in a larger drum.

The invention is illustrated in two sheets of drawings wherein:

35 Figures 1, 2 and 3 are diagrammatic illustrations of the end view of applicant's drum illustrating how it functions;

Figure 4 is a transverse section and Figure 5 a longitudinal section of a preferred embodiment of applicant's invention;

Figures 6 and 7 are schematic illustrations of a locking means movable in a straight line as contrasted to a rotating movement illustrated in the preferred form;

Figure 8 is a schematic illustration of a second embodiment of applicant's invention wherein the locking and tension shoes possess cam surfaces;

Figure 9 is an end view of a third embodiment of applicant's invention illustrating adaptation of applicant's locking means to a larger drum which carries an arbor;

Figure 10 is a fourth embodiment of the invention showing a cylindrical rubber segment for replacing the coil springs; and

Figure 11 is a fifth embodiment of the invention showing the use of shaped steel springs.

Continuing to refer to the drawings and particularly to Figure 1, a diagram, applicant's fundamental objective of locking one end and then on the same locking movement gripping the other end and pulling the strip tightly and evenly around the drum is attained by a locking shoe 10, a cam 12, a tension shoe 14, all functioning in a cylindrical recess 16 in a drum 18, the surface 20 of which is connected to the cylindrical recess by a slot 22. The cam 12 is pivoted on an axis 24 which is approximately the axis of the drum 18, there being permitted a radially directed displacement to accommodate different thicknesses of emery cloth to be explained hereinafter. When the cam is in the position shown in Figure 1, the locking shoe 10 under pressure from a spring 26 provides an opening 28 between its end 30 and the adjacent wall of the recess 16 into which may

be readily slipped one end 32 of an emery cloth strip 34. The emery surface of the strip which provides a purchase between the cloth and a smooth steel surface is outwardly directed and hence is engaged by the surface 34 of the locking shoe 10.

Turning the cam 12 one hundred and fifty degrees, results, referring to Figure 2, in locking the shoe 10 against the end 28 of the emery strip 34 while concurrently permitting the tension shoe 14 to move inwardly under the influence of springs 36 and 38 but only for a limited distance because of control means not here shown. This leaves an opening 48 between the end 42 of the tension shoe 14 and the cam 12 into which may be readily inserted the other end 44 of the emery strip 34.

It will be observed that the emery surface engages the surface of the cam, which is the rotating surface, while the smooth under surface of the strip 34 engages the shoe. Further clockwise rotation of the cam results in the leading edge 46 of the cam 12 to engage the end 44 and squeeze it against the tension shoe 14. At this moment, both ends of the emery strip 34 are tightly held between the cam 12 and shoes 10 and 14 respectively, but the strip 34 is not drawn tightly around the drum. On the contrary it is loose, or at least no tighter than the workman can make it by pulling the strip around the drum manually. This is the practical limit of usefulness of the locking means of existing drums because these locking means are working against the smooth under surface of the emery strip, which provides no purchase and hence will not tighten.

Further clockwise motion of the cam 12 results in the under side of the end 44 slipping along the smooth surface of the tension shoe while the emery side engaging the rotating cam will not slip and has no alternative but to pull up the strip tightly around the drum, as illustrated in Figure 3. The emery surface on applicant's drum is far smoother, i. e., more perfectly cylindrical, than can be obtained by a sleeve mounted on either a solid rubber core or a pneumatic core. As sleeve mounted drums are turned up to speeds exceeding 5,000 R. P. M., there develops a whistling which demonstrates variations of the emery grinding surface from the desirable cylindrical form, a sound absent when applicant's drum is turned up to 20,000 R. P. M.

Diagrammatic drawings and the foregoing illustration best illustrate the means for locking the two ends of an emery strip in applicant's drum and drawing the strip tightly around the drum by a single clockwise motion of the wrist. As thus far described, applicant's drum and locking means is designed for a given thickness of emery cloth with a slight range in thickness. One major feature of applicant's device is the automatic adjustability of the locking means to a wide range of thicknesses together with simple manual means for further increasing the range. This function is attained by permitting the cam 12 to move laterally under the control of springs. Because the thickness of emery papers having a range of 50 to 250 grits is actually a variation of a fraction of an inch, this feature can best be explained by describing applicant's preferred form of drum, giving exact dimensions of critical parts of the locking device.

Referring now to Figures 4 and 5, applicant's drum consists of an aluminum member 50 having a drum proper portion 52 and a hub 54 formed integrally therewith. The drum 52 contains a cylindrical recess 56 and the hub is centrally

bored and threaded at 58. A shank 60 having a shoulder 62 and an externally threaded portion 64 is made of hardened steel tightly-seated in the hub 54. The portion 64 contains a cylindrical recess 66 which is referred to herein as the cam stud seat 66. The hub 54 is drilled and threaded at 68 and 70 and after the shank 60 has been tightly seated in the hub, openings 72 and 74 are drilled so that they will be in exact alignment with the threaded openings 68 and 70.

A came 76 having the cross-sectional configuration shown in Figure 4 has an axially extending stud 78 which has an outside diameter substantially less than the inside diameter of cam stud seat 66. The face 77 of this stud may be smooth or if additional gripping power is desired, it may be knurled. The shoulder 80 of the came 76 engages both the shank and the end wall of the cylindrical recess 56 so as to limit the penetration of the stud 78 into the cam stud seat 66. A raceway 82 in the stud 78 receives balls 84 and 86 which are adjustably urged inwardly by a spring and a pair of lockable set screws, such as 88, 90 and 92. A keyway 94 is broached in the came 76.

Referring now to Figure 4, the locking shoe 96 is a segment of a cylinder of uniform thickness and has an outside diameter slightly less than the diameter of the cylindrical recess 56. The length of the lock shoe 96 is coextensive with the length of the recess 56. Its upper outside edge may have a plurality of wales 97 to grip better the emery cloth. Along two spaced radial lines which intersect a plan that bisects the shoe 76 and contains its axis, are cut two holes, such as 98, in each of which is fixedly mounted a lock shoe pin 100. A pair of holes, such as 102, are cut in the drum member 52 so as to be in axial alignment with the lock shoe pins and in these holes are positioned expansion springs and set screws, such as 104 and 106. The tension shoe 108 has a uniform thickness and has the same degree of curvature as the lock shoe 96. Two holes, such as 110, laterally spaced in a line which bisects the shoe, are threaded to receive two tension shoe guide screws, such as 112, each of which has a head 114. Each guide screw 112 is reciprocable in a hole 116 in the drum member 52 and limits movement of the tension shoe 108 inwardly of the recess 56 to a short distance when the head 114 engages the shoulder 118. Two sets of threaded holes, such as 117 and 119, contain two sets of expansion springs adjustably controlled by set screws, such as 120, 122, 124 and 126. The angularity of the sets of holes, such as 117 and 119, with respect to the axis of the hole 116 is not believed to be important other than that they should be approximately equal.

The drum member 52 contains two radial slots designated by the numbers 128 and 130. Slot 130 is cut for the purpose of assisting in balancing the drum—exact balance being obtained by adding or cutting away metal during a balancing test in a well-known manner. The slot 130 does not exist for the purpose of making it possible to feed in the ends 132 and 134 of an emery strip 136. The ends 128 and 134 can be fed only through the slot 128.

It is evident that the shoe and cam assembly will hold a position in the cylindrical recess 56 which is a resultant of the forces exerted by the various springs in the drum member 52. It is further evident that the cam 76 may move vertically by a distance at least equal to the clearance between the stud 78 and the cam stud seat 66. In a commercial embodiment wherein the

cam stud seat is .265 inch, the cam stud is .235 inch, so that the difference is .030 inch. In fact, a considerably greater play is permitted the cam 76 which may rock a little lengthwise during a tightening step. Thus, in the same commercial embodiment the circular surface of the cam has a diameter of .625 inch while the inside diameter of either shoe is .687 inch, a difference of .062. Moreover, the outside diameter of the shoes is slightly less than the diameter of the recess 56 so that there is little play here. The springs, such as 104, located where they are toward the lower side of the lock shoe 96 tend to thrust the shoe upwardly toward the slot 128. If the paper is thick this movement is much more limited than when it is thinner. It will be noted that the varying thicknesses of the emery cloth between the cam and the tension shoe are taken up by the springs which may exert more or less pressure in accordance with the position of the set screws.

The crux of this invention lies in providing two surfaces on the interior of the drum, i. e., a locking surface 140 and a tension surface 142, which in the case of surface 142 is smooth so as to assist in movement of the smooth undersurface of the emery strip. While the surface 142 is on the tension shoe 108 in this particular embodiment, it could be on the drum itself excepting for the desire to compensate for different thicknesses of emery cloth. In connection with these two surfaces, applicant uses an intermediate member such as the shoe 96 which engages the rough emery surface of the cloth and the cam 76 which engages both the locking shoe and the rough emery surface of the other end of the cloth. It is evident that the locking surface 140 instead of being curved could be flat or there could just be a single edge which was engaged by a member performing the function of the shoe 96. Similarly, the tension surface 142 could be flat or some other configuration which, however, might reduce the total area of the rough emery surface engaged by the locking means. In this respect, therefore, it is desirable that the inside curvature of the tension shoe 108 be approximately the same as the outside surface of the cam 76 so that the purchase obtained by the cam on the emery cloth increases as the emery cloth is drawn tightly and tends more to pull free.

By way of illustrating the basic principles of applicant's locking device, diagrammatic views 6 and 7 are shown in the drawings. Referring to Figure 6, a shoe 144 is movable horizontally toward and away from the surface 146 on the drum 148. A locking bar 150 is reciprocable vertically of the slot 152 which has a tension surface 154. The tension surface 154 is separated from the wall 156 of the slot by a shoulder. When the bar 150 is moved downwardly the lug 158 pushes the shoe 144 to the left so as to lock a piece of emery cloth. Further downward movement of the bar 150 so as to engage the other end 160 of emery cloth strip will first lock it against the tension surface 154 and further movement will pull it on down. Figure 7 shows the same construction with a locking bar 162 movable on a path at right angles to the principal axis of the slot. The invention disclosed in the major embodiment covers these two suggested devices.

Two other embodiments of the invention are shown in Figures 8 and 9. In the first embodiment, referring to Figure 8, the locking shoe 160 has greater thickness at the end 162 than at the end 164 and the tension shoe 166 has a greater

thickness toward its lower end. The cam member 168 has an outside diameter slightly less than that on the inside of the shoes, the curvature in all cases being true arcs of a circle. By rotating the cam, the locking shoe is locked upwardly, while the tension shoe is locked outwardly and downwardly.

In the embodiment shown in Figure 9, the drum 170 has a central arbor 172. This arbor is required in the case of larger drums, that is, drums some four inches to two feet, because the tools upon which they are mounted carry some form of spindle. It is impossible, therefore, to mount the locking means coaxially of the drum. In the form illustrated in Figure 9, two of applicant's locking means are shown balanced on opposite sides of the arbor.

Figures 10 and 11 illustrate two embodiments of the invention which may become the successful commercial embodiments of the invention. Drilling the principal housing as illustrated in Figure 4, seating the pins in the shoes and assembling the same with springs, constitutes a major element of cost in the embodiment first described. The embodiments shown in Figures 10 and 11 seek to eliminate what is believed to be avoidable construction. In Figure 10, the shoe 180 has the same shape as the locking shoe in other embodiments but it is forced toward the locking area 182 by a compressible cylindrical segment 184 so as to perform the same function as the spring 104 in Figure 4. In order to prevent endwise displacement of the shoe, the cylindrical casting 186 has an annular channel therein into which the rubber pressure member 184 and the shoe 180 may be slipped. With respect to the tightening shoe, the rubber cylindrical segment 188 extends in almost a 180 degree arc.

Referring to Figure 11, the rubber cylindrical segments 184 and 188 of Figure 10 have been replaced by spring members 190 and 192.

Having thus described my invention, what I claim as new and wish to secure by United States Letters Patent is:

1. A buffing drum comprising a cylinder, an arbor mounted axially on one side of said cylinder, a transverse passageway diametrically through said cylinder, a cylindrical chamber axially positioned in said cylinder, a pair of shoes each in the shape of a cylindrical segment and one positioned adjacent the chamber wall on one side of the passageway and the other positioned adjacent the chamber wall on the other side of the passageway, and a semi-cylindrical locking element axially positioned in the chamber and having its outer surface engageable with the inner surface of the shoes.

2. A buffing drum comprising a cylinder, a pair of spaced, facing walls extending inwardly from the cylinder surface and parallel to the cylinder's axis, a holding shoe movable toward one of said walls, a locking member movable toward the other wall, and means on the locking member for pressing the holding shoe against its wall as the locking member moves toward its associated wall.

3. A buffing drum comprising a cylinder, a pair of spaced, facing walls extending inwardly from the cylinder surface and parallel to the cylinder's axis, a holding shoe movable toward one of said walls, a locking member, a surface on the locking member directed toward the second wall and complementary thereto for flush engagement therewith and for sliding along said surface, and means on the locking member for pressing the holding

shoe against its associated wall as the complementary surface of the locking member slideably engages its associated wall.

4. A buffing drum comprising a cylinder, a cylindrical chamber therein having an axis parallel to the axis of said cylinder, a passageway having a rectangular cross section connecting the surface of the cylinder to the cylindrical chamber, a holding shoe movable toward one wall of the chamber that extends parallel to the axis of the cylinder, an insert having a thickness substantially equal to that of the shoe positioned against the wall of the chamber adjacent the opposite wall of the passageway, and a rotatable member positioned substantially coaxially of the chamber said rotatable member having a curving external surface concentric with the wall of the chamber and having a radius sufficient to press the holding shoe and the insert toward the walls of the chamber.

5. A buffing drum comprising a cylinder, a cylindrical chamber coaxially positioned therein, a slot connecting the cylinder's surface with said chamber, an axially rotatable member in said chamber having a surface consisting of a segment of a cylinder, and a pair of shoes in the shape of cylindrical segments positioned between said rotatable member and the walls of said chamber.

6. A buffing drum comprising a cylinder, a cylindrical chamber coaxially positioned therein, a passageway having spaced, facing walls extending lengthwise of the cylinder's axis and connecting the cylinder's surface with said chamber, an axially rotatable member in said chamber having a surface consisting of a segment of a cylinder, a pair of shoes in the shape of cylindrical segments positioned between said rotatable member and the walls of said chamber, and means engageable with each shoe for preventing rotative movement of the same.

7. A buffing drum comprising a cylinder, a cylindrical chamber coaxially positioned therein, a passageway having spaced, facing walls extending lengthwise of the cylinder's axis and connecting the cylinder's surface with said chamber, an axially rotatable member in said chamber having a surface consisting of a segment of a cylinder, and a pair of shoes in the shape of cylindrical segments positioned between said rotatable member and the walls of said chamber, said shoes having their outer surfaces curved on a shorter radius than the wall of the chamber and their inner surfaces curved on a greater radius than the surface of the rotatable member.

8. A buffing drum comprising a cylinder, a cylindrical chamber therein having an axis parallel to the axis of the cylinder, a passageway having spaced, facing walls extending lengthwise of the cylinder's axis and connecting the cylinder's surface to said chamber, an axially rotatable member in said chamber having a surface consisting of a segment of a cylinder, and a pair of shoes in the shape of cylindrical segments positioned between said rotatable member and the walls of said chamber.

9. A buffing drum comprising a cylinder, a cylindrical chamber therein having its axis parallel to the axis of the cylinder, a passageway having spaced, facing walls extending lengthwise of the cylinder's axis and connecting the cylinder's surface to said chamber, an axially rotatable member in said recess having a surface consisting of a segment of a cylinder, a pair of shoes in the shape of cylindrical segments oppositely disposed between said rotatable member and the walls of said recess so that one end of each shoe is adjacent to the passageway, and spring means urging both shoes toward the rotatable member.

10. A buffing drum comprising a cylinder, a cylindrical chamber coaxially positioned therein, a passageway having spaced, facing walls extending lengthwise of the cylinder's axis and connecting the cylinder's surface to said chamber, an axially rotatable member in said chamber having a surface consisting of a segment of a cylinder, a pair of shoes in the shape of cylindrical segments oppositely disposed between said rotatable member and the walls of said chamber so that one end of each shoe is adjacent to the slot, and spring means urging both shoes toward the rotatable member.
